Primary Examiner — Selina Sikder(74) *Attorney, Agent, or Firm* — Price Heneveld LLP;
 Brian James Brewer(57) **CLAIM**

I claim the ornamental design for a lighting control wand, as shown and described.

DESCRIPTION

FIG. 1 is a top, front perspective view of a lighting control wand of the present disclosure;

FIG. 2 is a top, rear perspective view of the lighting control wand of FIG. 1;

FIG. 3 is a bottom, front perspective view of the lighting control wand of FIG. 1;

FIG. 4 is a bottom, rear perspective view of the lighting control wand of FIG. 1;

FIG. 5 is a first side elevational view of the lighting control wand of FIG. 1;

FIG. 6 is a second side elevational view of the lighting control wand of FIG. 1;

FIG. 7 is a top plan view of the lighting control wand of FIG. 1;

FIG. 8 is a bottom plan view of the lighting control wand of FIG. 1;

FIG. 9 is a front elevational view of the lighting control wand of FIG. 1; and,

FIG. 10 is a rear elevational view of the lighting control wand of FIG. 1.

The broken lines depict portions of the article that form no part of the claimed design.
